UNITED STATES PATENT OFFICE.

MAE H. SCHWINGER, OF SAN FERNANDO, CALIFORNIA, ASSIGNOR OF ONE-HALF TO FANNIE M. BAILARD, OF CARPINTERIA, CALIFORNIA.

DESIGN FOR A STATUETTE.

• 60,884.

Specification for Design.

Patented Apr. 18, 1922.

Application filed September 15, 1921. Serial No. 500,977. Term of patent 3½ years.

To all whom it may concern:

Be it known that I, MAE H. SCHWINGER, a citizen of the United States, residing at San Fernando, in the county of Los Angeles and State of California, have invented a new, original, and ornamental Design for a Statuette, of which the following is a specification, reference being had to the accompanying drawing, forming a part thereof.

I claim:

The ornamental design for a statuette as shown.

MAE H. SCHWINGER.
